APPARATUS FOR CLEANING CANS

Thomas F. Clark, Peoria, Ill., assignor to the
United States of America as represented by the
Secretary of Agriculture

Application August 22, 1951, Serial No. 243,146

2 Claims. (Cl. 51—15)

(Granted under the act of March 3, 1883, as
amended April 30, 1928; 370 O. G. 757)

1

The invention herein described may be manufactured and used by or for the Government of the United States of America for governmental purposes throughout the world without the payment to me of any royalty thereon.

This invention relates to a method and an apparatus for cleaning containers, such as metal cans. It particularly relates to cleaning metal milk cans prior to retinning.

Milk cans must be cleaned and reconditioned from time to time to remove milk residues, dirt, foreign material, rust and other corrosion residues prior to retinning. The retinning of milk cans has heretofore resulted in an excessive number of rejected and recycled cans, because of faulty cleaning.

Prior to my invention, salvaging of cans, such as metal milk cans, has required a large amount of costly hand labor and chemicals. It has customarily included alkaline and acid treatments involving scrubbing and scouring with brushes, and steel wool, and, unless carried out with extreme care and skill, the hand cleaning, especially on inner surfaces of the cans, often results in non-uniform cleaning and actual loss of the residual protective coating surfaces by abrasion and chemical action.

According to this invention, means are provided for cleaning milk and other cans, and cylindrical-type objects generally, by subjecting the surfaces to be cleaned to a blast of soft grits. The term "soft grits" as used herein refers to such materials as ground corncobs, pecan shells, filbert shells, walnut shells or similar materials. These grits, alone or in admixture with each other, may be further mixed with varying proportions of rice hulls. Soft grit blasting is advantageous, since it effects removal of the objectionable materials from the can surfaces without damage to the container itself. This principle, when applied using the device of this invention, makes possible rapid and uniform cleaning with a minimum of hand labor. When so cleaned the can is ready for the light pickling operation prior to retinning. Frequently the pickling may be omitted and the can sent directly to retinning.

The novel apparatus is illustrated in the accompanying drawings.

Figure 1 is an assembled view of the cleaning blast chamber and pressure tank means to feed blasting grits thereto;

Figure 2 is a horizontal cross-section of the blast chamber, at plane 2—2 of Figure 3;

Figure 3 is a vertical cross section of the blast chamber;

2

Figure 4 is a vertical section of a modified form of one-half of an air and grit mixing and feeding valve.

Referring to Figure 3, the apparatus is shown with a milk can 1 in cleaning position. The can rests on platform 2, which is a rotary table preferably made of a perforate grating and having an aperture 200 over which the open end of the can rests. Blast nozzles 201 and 202 are connected by means of supporting pipes 401 and 402 and flexible connections 203 and 204 with a source 22 of a mixture of air and grits. The blast nozzles are each secured rigidly to bracket members 5 and 6 situated in guiding groove 15 of elevating mechanism 16. These bracket members have screw threaded bores that mesh with vertical worm shaft 7 which is driven by worm-and-gear arrangement 8. Shaft 80 drives the worm-and-gear arrangement, thus causing members 5 and 6 to move in a vertical direction. Shaft 80 is connected to a power source through a reversing mechanism, not shown, so that brackets 5 and 6 and the nozzles move up and down in oscillatory manner. The reversing mechanism is adjustable, by means well known in the art to raise and lower the blast nozzles the proper distance for blast-cleaning the entire length of the can. Nozzles 201 and 202 enter the blast chamber through vertically movable wall sections 301 and 302 that restrain the soft grits within the chamber, yet allow vertical motion required of the nozzles and their lines. Sections 301 and 302 need not be in vertical alignment, to avoid interference.

Cooperating with the vertical movement of the nozzles, table 2 rotates so that the entire surface, inside and out, of the can is effectively blasted by the nozzles. The table is made to rotate by V-belt drive 205, the V-shaped groove 206 encircling the table. The rotating table is supported upon rollers 9 and is centered by rolling guide members 10. The guide members have an overhanging flange at 11 to guide the outer edge of the table.

The blast cleaning mechanism is provided with a housing 12 having an upper dust outlet 14 and a lower recovery hopper 13.

As may be seen from the drawings, my apparatus consists essentially of a rotating table upon which cans to be cleaned may be placed. In operation, a system of multiple blast nozzles, for blasting inside and outside the can, move vertically with respect to the can so that effective cleaning is obtained over all the surfaces of the can.

55

Milk cans are frequently cleaned after the bottoms have been removed. Cans in this condition may obviously be placed upon the rotating table in either upright or inverted position. Moreover, my apparatus may be constructed in a simplified variation to clean bottomless cans. For example, nozzle 201 may be constructed to enter the can from above by obvious variations in construction of the worm shaft. This modified construction eliminates the necessity for the opening in the rotating table.

In operation, used blasting grits fall from the zone of blasting and are recovered for re-use from the recovery hopper and fed back into the tank 20, by any suitable screw conveyor (not shown).

Casing 20 is a pressurized tank containing soft grits. The grits flow through grit control valve 21 into duplex manifold 22 which is a mixing chamber for grits from 21 and air from 19. This supplies streams of grit for flexible lines 203 and 204. Dust from the cleaning chamber is exhausted by means of exhaust blower 25, sending the dust through line 26 to a dust collector, not shown. Used grits are removed from the cleaning chamber through dump valve 17.

Figure 4 illustrates a modified form of my invention in which the pressurized tank is eliminated. In this variation a double or duplex mixing valve 27 replaces the dump valve 17. This permits continuous recycling of grits from the hopper 13 of the cleaning apparatus back through the flexible lines to the blast nozzles. Compressed air is fed through line 28 to nozzle 33. Grits are received through opening 29 directly from hopper 13. Auxiliary air from the atmosphere enters through auxiliary air inlet 30. Figure 4 represents a cross section of one-half of the mixing valve. Each half is designed to feed one of flexible lines 203 and 204. Suitable valves commonly known in the art are used as a means for regulating the air which in turn controls the flow of grits.

It will be obvious to anyone skilled in the art that either the rotating table or the multiple nozzle system may move vertically. It is only necessary that there be relative movement. Similarly, there may be more than two blast nozzles, and they may be constructed to best direct the cleaning blast against special shapes and surfaces to be cleaned. Moreover, the speed of vertical movement may be variable. This can be accomplished by well-known mechanisms co-operating with the reversing mechanism and the drive shaft. The particular means for accomplishing the rotating motion of the table and the vertical movement may vary widely.

Likewise, the rotation of the can with respect to the nozzle system may be accomplished by rotating the nozzle system with respect to the table. The nozzles may be separately operable and movable, for example, by means of cut-off valves in the blast stream and by separately actuated elevating mechanisms. Other variations in construction will be apparent to those skilled in the art, and are within the scope of my invention.

I claim:

1. An apparatus for blast cleaning the inner and outer surfaces of a vessel comprising: a

housing, a horizontal table within the housing mounted for rotation about a vertical axis and adapted to support the vessel, the table having a central opening for communicating with the inside of the vessel when the latter is inverted thereon, an outer blast nozzle directed inwardly to clean the outer surface of the vessel, an inner blast nozzle directed outwardly to clean the inner surface of the vessel, means for turning the table, a supporting conduit connected to each nozzle, the conduit for the inner nozzle passing upwardly through the opening in the table, the supporting conduits passing laterally through the housing side wall, means mounted outside the housing to raise and lower the two supporting conduits substantially the length of the vessel to be cleaned, plate means movable with each conduit on the said housing wall to keep the wall closed, passageways adjacent the periphery of the table permitting the egress of air upwardly in the housing outside the vessel being cleaned, an air-dust vent for the housing above the table, means for withdrawing air and dust through said vent, air-grits mixing means to supply a blast of air and cleaning grits to each of said conduits and thence to the nozzles, supporting roller means below and adjacent the periphery of the table, guide means for the periphery of the table, and a hopper attached to the lower part of the housing to collect the spent grits below the table.

2. An apparatus for blast cleaning the inner and outer surfaces of a vessel comprising: a housing, a rotatable table within the housing adapted to support the vessel and having a central opening which communicates with the inside of the vessel, an outer blast nozzle directed inwardly to clean the outer surface of the vessel, an inner blast nozzle directed outwardly to clean the inner surfaces of the vessel, an inner blast nozzle feed pipe projecting upwardly through said opening, means for turning the table, supporting rollers below the table, guide means for the periphery of the table, means for reciprocating both of the nozzles the length of the vessel, air-grits mixing means to supply a blast of air and cleaning grits to said nozzles, a dust and air outlet for the part of the housing above the table, a hopper attached to the lower part of the housing to collect the spent grit below the table, and air passages adjacent the perimeter of the table to permit upward movement of air to said outlet.
